UNITED STATES PATENT OFFICE.

RICHARD G. TULLER, OF MARYLAND, NEW YORK.

DOOR-SECURER.

1,282,989.

Specification of Letters Patent.

Patented Oct. 29, 1918.

Application filed June 17, 1918. Serial No. 240,366.

To all whom it may concern:

Be it known that I, RICHARD G. TULLER, a citizen of the United States, residing at Maryland, in the county of Otsego and 5 State of New York, have invented a new and Improved Door-Securer, of which the following is a specification.

My invention has reference to improvements in that type of locking devices which 10 may be readily carried upon the person and secured to and detached from a door jamb.

Primarily, my invention has for its object to provide a device of the character stated, of a simple and economical construction, that is particularly adapted for use by 15 travelers for the purpose of temporary application to the door frame of a room at hotels or other stopping places, the locks of which are commonly of that type that afford 20 little or no protection against being picked or broken.

Another object of my invention is to provide a device of the type stated, in which the locking elements are so arranged that 25 the device may be readily applied and secured to a right or left hand opening door and the said elements readily adjusted for doors of different thicknesses and in which the parts are co-operatively so assembled and 30 are of such strength that when applied, the door cannot be opened without destroying or breaking it or mutilating the framing.

For a full, clear and complete disclosure of my invention reference is to be had to the 35 following description, the claims, in which the invention is specifically pointed out, and to the drawings, in which:

Figure 1 is a perspective view of my invention, so much of a door and its casing 40 being shown as is necessary to illustrate the operative application of my improved device, the latter being shown adjusted for holding the door closed.

Fig. 2 is a similar view, the adjustable locking element being shown swung out to its longitudinally shiftable position.

Fig. 3 is a horizontal section taken practically on the line 3—3 on Fig. 5.

Fig. 4 is a transverse section thereof on 50 the line 4—4 on Fig. 3.

Fig. 5 is a rear face view of the device.

My improved device consists generally of a body plate 1, preferably of steel, whose opposite ends are thinned to facilitate 55 either of such ends for fitting between the door jamb and the door edge and each of

the said ends is formed, on the rear face thereof, with one or more spurs 2, of sufficient length that, when inserted in the lockkeeper on the jamb, they secure or hold 60 the body plate from being pulled or pushed out, when the door is closed, as indicated in Figs. 1 and 3.

The central or thickened portion of the body plate 1 has a longitudinal slot 3, the opposite edges 30—31 of which are formed with locking teeth 30^a—30^b and one of the said toothed portions 30 is of substantially semi-circular shape in cross section, see Fig. 4, the reason for which will presently appear.

The locking element consists of an elongated member 4, the main portion of which is of substantially the thickness of the slotted portion of the body 1 and of somewhat less length than the slot therein, as is best shown in Fig. 3.

At the opposite ends, the member 4 has outwardly extended heel portions 40—40 that constitute stops for engaging with the 80 inside of the door, when adjusted thereagainst, as shown.

One edge of the main portion of the member 4 has integral hook-like members 41—41 that engage the rounded edge of the toothed portion 30 of the body, see Fig. 4, and constitute hinged members that provide for readily swinging the locking element 85 out of the slot 3 and out of the way, when closing the door onto the body 1, as illustrated in Fig. 2.

The opposite edges of the member 4 have teeth 42—42 that interlock with the teeth 30^a—30^b on the body 1, when the said member is swung into the locking position and to facilitate the manipulation of the member 4, a turn button 5 is attached thereto and which includes a shank 50 that passes through the said member 4 and carries a latch 51 at the inner end which, when the button 5 is adjusted as in Figs. 1, 3 and 5, 90 swings over the inner face of the body 1 and locks the member 4 against swinging out of its interlocked engagement with the said body.

From the foregoing description taken in connection with the accompanying drawings, the complete construction, the manner of its application, and the advantages of my device will be readily apparent.

What I claim is:

1. A door securer comprising a body plate

adapted to be inserted between two members to be locked, one of the said members being movable away from the other member, the said body plate having a spur adapted to project into a recess in the jamb, a locking element hingedly mounted upon and having longitudinal adjustment relatively to the said body plate, the said element including a stop portion adapted to be shoved up against the movable member, the said hinged element and the body portion having locking teeth that interengage when the locking element is swung to the locking position.

2. A lock device of the character described, comprising a main body plate having one of its ends adapted to be inserted between a door and its adjacent jamb and provided with a casing spur adapted to project into a recess in the jamb, the said body plate having a longitudinal slot formed with locking teeth along the opposite edges thereof, a locking element which includes a body portion insertible into the slot of the body plate and of less length than the said slot, the said locking element having locking teeth along its opposite edges for interengaging with the teeth on the slot edges, the said body portion of the locking element including a stop member adapted to be projected against the door and means for holding the locking element in interlocked engagement with the slotted body, the said means consisting of a turn button having a shank that extends through the locking element and a latch on the inner end of the shank movable over the rear face of the slotted body.

3. A locking device of the character described, comprising a main body plate having one of its ends adapted to be inserted between a door and its adjacent jamb and provided with a casing spur adapted to project into a recess in the jamb, the said body plate having a longitudinal slot formed with locking teeth along the opposite edges

thereof, a locking element which includes a body portion insertible into the slot of the body plate and of less length than the said slot, the said locking element having locking teeth along its opposite edges for interengaging with the teeth on the slot edges, the said body portion of the locking element including a stop member adapted to be projected against the door and means for holding the locking element in interlocked engagement with the slotted body, the said means consisting of a turn button having a shank that extends through the locking element and a latch on the inner end of the shank movable over the rear face of the slotted body.

4. As a new article, a door securer comprising a main or body plate whose opposite ends are shaped for being inserted between a door and its jamb, each of said ends having a spur adapted to project into a recess in the jamb, the central portion of the body having an elongated slot whose opposite edges have locking teeth, one of the toothed portions of the said body having a rounded outer edge and a locking element consisting of a body portion of less length than that of the slot in the body plate and having teeth at the opposite edges for interlocking with the toothed edges of the slotway, said locking element having its ends formed with outwardly projected heel portions that constitute stops for being brought into engagement with the door, said locking element being hingedly mounted on the rounded outer edge of the main or body plate to swing outwardly from the said plate, and means on the said locking element for securing such locking element to its adjusted positions on the main or body plate.

RICHARD G. TULLER.
